VARIABLE REACTANCE

Walter van B. Roberts, Princeton, N. J., assignor
to Radio Corporation of America, a corpora-
tion of Delaware

Application August 25, 1942, Serial No. 456,018

2 Claims. (Cl. 179—171.5)

In this application I have disclosed a new and improved reactance tube arrangement wherein a tube is so arranged and connected that a substantially constant conductance component together with a variable susceptance component is produced across two terminals at which alternating voltage appears. The susceptance component may be varied by varying the tube plate resistance, and in my improved circuit means is provided for producing said variations of susceptance without causing at the same time changes in the conductance component.

Such an arrangement is of particular value in oscillator frequency control systems because by the use of the same, frequency control of the oscillations is accomplished without change in the amplitude thereof.

In describing my invention in detail reference will be made to the attached drawing wherein Figure 1 is a basic tube circuit adapted to be arranged and operated to provide a variable susceptance component without substantial variation of the conductance component. Figure 2 is a graph showing the admittance characteristic of the tube circuit of Figure 1 when Z is a pure reactance.

Figure 3 is an illustrative practical embodiment of my novel controlled reactance arrangement including means for supplying modulation voltage and adapted to be connected to a wave source to control the wave length of the same without changing substantially the amplitude thereof.

In Figure 1, Z is assumed to be a pure reactance in which case the effective admittance to the voltage E is shown in Figure 2 by the circle diagram, the various points on the circle corresponding to various values of plate resistance R of the tube. This diagram is for the case where Z is an inductance. However, Z could be a capacity with the result that the circle would be above the horizontal axis of the diagram. Furthermore, Z may be complex and still a circle diagram will result from varying R. So long as a circle results which has a vertical portion, the arrangement has the property that a small variation in R will vary the susceptance of the system without substantially changing the conductance. Hence, if the operating point is chosen to fall on the vertical part of the circle diagram, the arrangement can be used as a reactance tube to frequency modulate an oscillator, for example, without introducing appreciable amplitude modulation. The proper operating point is

chosen preferably by choosing Z to satisfy the condition $R=|Z|(\mu+2)$.

That I have provided a tube circuit wherein a constant conductance and variable susceptance is developed is proven mathematically hereinafter.

In Figure 1 assume Z is a pure reactance.

R_p is the tube plate impedance, and i_p is the plate current, and μ the amplification constant of the tube.

From elementary considerations,

$$i_p = [E - e_c - \mu(e_c)] \div (R_p + Z)$$

but, $e_c = i_p Z$ is the voltage across Z

$$\therefore i_p = \frac{E}{R_p + Z(\mu+2)}$$

When $R_p=|Z|(\mu+2)$ the conductance component of i_p/E is maximum and changes very little (for small changes of R_p) compared to the variations of susceptance. At this operating point this susceptance is

$$\frac{1}{\sqrt{2}} \times \frac{1}{\sqrt{2R_p}} = \frac{1}{2} \times \frac{1}{R_p}$$

If we assume Z is a pure inductance, then we have an admittance characteristic as illustrated in Figure 2.

Figure 3 shows a practical embodiment of the invention where an inductance L is used in the cathode circuit and a capacity C is put in shunt to the whole system. This capacity is chosen to wipe out all susceptance from the system in the absence of control voltage at AF. Thus, if the set-up is used for FM, the mean frequency of the oscillator is not affected by the connection of the reactance tube system.

The required value of L to provide constant conductance is given by

$$2\pi f L = \frac{R_p}{\mu+2}$$

where f is the mean frequency, and R_p is the value of plate resistance corresponding to a desired bias on the tube. C is then chosen to satisfy

$$2\pi f C = \frac{1}{2} \frac{1}{R_p}$$

It is also possible to employ capacitive reactance in Z and to shunt the arrangement with an inductance in place of the element C of Figure 3. However, the first discussed arrangement is preferred since the inductance in the cathode lead provides a direct current path for space current, while the shunting condenser C absorbs distributed capacity to ground of the plate circuit.

I claim:

1. In a system of the nature described, a tube having electrodes including an anode, a cathode, and a control grid, a pair of terminals between which a variable susceptance is to be produced, a low impedance connection from the anode to one terminal, a connection including reactance between the cathode and other terminal, a direct current source connected between the anode and cathode, means for supplying an operating bias between the grid and cathode, means for superposing modulating voltage on said bias whereby an effective susceptance is developed between said terminals, said reactance being chosen to satisfy the equation $R_p = |Z|(\mu+2)$ (where R_p is the tube anode resistance, Z is the reactance of the cathode lead and μ is the amplification constant of said tube).

2. In a system of the nature described, a tube having electrodes including an anode, a cathode,

and a control grid, a pair of terminals between which a variable susceptance is to be produced, a low impedance connection between the anode and one terminal, a connection including reactance between the cathode and other terminal, a direct current source connected with the anode and cathode, means for supplying an operating bias between the grid and cathode, means for superposing modulating voltage on said bias whereby susceptance is developed between said terminals, said reactance being chosen to satisfy the equation $R_p = |Z|(\mu+2)$ (where R_p is the tube anode resistance, Z is the reactance of the cathode lead and μ is the amplification constant of said tube), a susceptance of sign opposite to that in the said cathode lead connected across said terminals and of a size such as to make the effective susceptance between said terminals zero in the absence of modulating voltages whereby alternating current modulating voltages cause solely alternating values of susceptance between said terminals.
